(57) **CLAIM**

The ornamental design for a tyre tread, as shown and described.

DESCRIPTION

1. Tyre tread
- 1.1 : Perspective
- 1.2 : Front
- 1.3 : Left
- 1.4 : Enlarged
- 1.5 : Enlarged
- 1.6 : Cross sectional
- 1.7 : Cross sectional

Fig.1.3 is a left view of a tyre tread, the right view being identical; Fig.1.4 is a fragmentary enlarged perspective view surrounded by line 4-4 and line 4'-4' in Fig. 1.1; Fig.1.5 is a fragmentary enlarged front view surrounded by line 5-5 and line 5'-5' in Fig. 1.2; Figs.1.6 and 1.7 are cross-section views taken along lines 6-6 and 7-7 in Fig.5 respectively; In the drawings, the pattern repeats uniformly throughout the circumference of the tyre tread, and broken lines depict environmental subject matter only and form no part of the claimed design.
